SCREEN DOOR GRILLE

Frank C. Endean, Erie, Pa.

Application July 6, 1959, Serial No. 56,657

Term of patent 14 years

(Cl. D54—2)

FIG. 2

Fig. 1 is a front elevational view of a screen door grille, showing my new design; and

Fig. 2 is a top edge view.

I claim:

The ornamental design for a screen door grille, substantially as shown.
